No. 37,073.

Patented August 9, 1904.

UNITED STATES PATENT OFFICE.

ROBERT KINTZ, OF MERIDEN, CONNECTICUT, ASSIGNOR TO INTERNATIONAL SILVER CO., OF MERIDEN, CONNECTICUT, A CORPORATION OF NEW JERSEY.

DESIGN FOR A BORDER FOR VESSELS OR SIMILAR ARTICLES.

SPECIFICATION forming part of Design No. 37,073, dated August 9, 1904.

Application filed July 14, 1904. Serial No. 216,624. Term of patent 7 years.

To all whom it may concern:

Be it known that I, ROBERT KINTZ, of Meriden, in the county of New Haven and State of Connecticut, have invented a new and original ornamental Design for a Border for Vessels or Similar Articles; and I do hereby declare the accompanying drawing to be a full, clear, and exact illustration of the same, and which said drawing constitutes part of this specification

and represents a face view of a border for vessels or similar articles embodying my design.

I claim—

The ornamental design for a border for vessels or similar articles as shown.

ROBERT KINTZ.
